(57) **CLAIM**

The ornamental design for a toy scoop and gatherer set, as shown and described.

DESCRIPTION

FIG. 1 is a front perspective view of the scoop and gatherer set showing my new design;

FIG. 2 is a top plan view of the scoop alone;

FIG. 3 is a side elevation view thereof, the opposite side elevation view being a mirror image of that shown;

FIG. 4 is a front elevation view of the scoop alone;

FIG. 5 is a rear elevation view thereof;

FIG. 6 is a bottom plan view thereof;

FIG. 7 is a bottom front perspective view of the scoop alone;

FIG. 8 is a front perspective view of the gatherer alone;

FIG. 9 is a rear isometric view of the gatherer alone; and,

FIG. 10 is an enlarged side elevation view of the gatherer alone, the opposite side elevation view being a mirror image of that shown.

FIG. 11 is front perspective view of a second embodiment of the scoop and gatherer set of FIG. 1, comprising the scoop and gatherer with bristles on the edge of the gatherer element;

FIG. 12 an enlarged side elevation view of the gatherer alone,

in the second embodiment with bristles attached to the bottom edge.

FIG. 13 is an enlarged side elevation view of the gatherer of a third embodiment of the scoop and gatherer set of FIG. 1, comprising the gatherer with a soft material edge; and,

FIG. 14 is a rear isometric view of the gatherer alone, in the third embodiment with the soft material attached to the bottom edge of the gatherer.

The different elements of the claimed design are being shown separated in some figures for convenience of illustration. The broken lines showing in FIGS. 2, 5, 9, and 14 are for illustration purposes only and form no part of the claimed design.
